J. W. LESLIE

METHOD OF AND APPARATUS FOR STRAPPING BOXES

Filed Aug. 2, 1921

UNITED STATES PATENT OFFICE.

JOHN W. LESLIE, OF EVANSTON, ILLINOIS.

METHOD OF AND APPARATUS FOR STRAPPING BOXES.

Application filed August 2, 1921. Serial No. 489,366.

To all whom it may concern:

Be it known that I, JOHN W. LESLIE, a citizen of the United States, and resident of Evanston, in the county of Cook and State 5 of Illinois, have invented certain new and useful Improvements in Methods of and Apparatus for Strapping Boxes, of which the following is a specification.

This invention relates to a method of and 10 apparatus for applying tensional binders such as metallic box strapping or the like to boxes and packages in a novel and efficient manner; and to apparatus suitable for the practice of such method.

15 In the application of tensional binders to boxes and packages, speed is a very important consideration.

The invention herein described very much increases the speed of application of 20 tensional binders by eliminating the most laborious part of the work heretofore necessary, namely the passing of the binder around a box or package prior to overlapping its ends, tightening it and forming 25 a joint.

In the drawings:—

Fig. 1 is a side elevation of a strapping bench used in connection with the invention,

30 Fig. 2 is a front elevation thereof, Fig. 3 is a diagrammatic view, illustrating the method of the invention,

Fig. 4 is a side elevation of a clip used in connection with the invention, and 35 Fig. 5 is a longitudinal section therethrough.

In order to eliminate the passing of the binder around a box 1, I arrange the box 1 adjacent to and having the axis around 40 which the binder is to be applied in the same general direction as that of the axis of coil 2 of strap. Strapping and other binder material is supplied in coils. The binder must therefore be drawn from the coil and applied to the box or package. The 45 free end 3 of the coil is held for convenience in a clip 4, later described, and a platform 5 at one end of the box is provided to hold the same in the position shown in Fig. 1. 50 The other end of the box may be supported by any suitable means (not shown).

With the parts in this position the operator taking the free end 3 of the strap in one hand and an intermediate portion 55 6 of its length in the other, simply moves a loop or convolution of this strap side-

wise from the coil to its proper position on the box. He then overlaps the ends, in the fashion indicated in dotted lines in Fig. 3 and proceeds to tighten and join the strap in the ordinary way, after which the strap on the coil side of the joint is broken off at the joint, the free end replaced in the clip 4, the box turned about to present its other end for the same operation, or, where 60 only one strap is placed about the box, a new box substituted to be treated in the same way.

By this means the operator, by simply withdrawing the convolution, preferably 70 from the inside of the coil, and having the box and coil in proper relative position, shifts the convolutions already formed in the coil, one by one, sidewise to the proper position on the box, and the hitherto time-consuming operation of revolving the entire coil, cutting off a strip of suitable length and passing the strap endwise about the box is completely eliminated.

I shall now describe a stand useful for 75 the practice of the foregoing method, certain parts of which stand have previously been referred to.

I provide a stand 7, preferably mounted 80 on casters 8, in which is mounted an arm 9, sloping outwardly and horizontally adjustable by the pin 10 and apertures 11, the arm 9 also being adjustable, so that it can be tilted more or less by the brace 12, adjustable by the pin 13 and apertures 14.

The arm 9 has at its end a clip 4, previously referred to, which comprises a supporting bar 15 which is secured to the arm 9 by the screws 16. A spring tongue 17 is likewise secured to the arm 9 by the screws 16, and its outer end carries a block 18 from the outer end of which projects a shaft 19. A roller 20 is rotatably mounted upon the shaft 19, the ends of which are tapered in opposite directions, as shown in Fig. 5, to permit the roller to oscillate slightly about a transverse axis. The upper side of the outer end of the bar 15 is beveled, as shown at 21, so as to permit the strip 3 to be easily inserted between the roller 20 and the bar 15.

A tubular guideway 22 is secured to the end of the arm 9 by the strap 23 and its lower end holds a quantity of oil-saturated waste 24 which is held downwardly against the upper side of the roller 20 by means of the weight 25.

The tool used for tightening a strap section about a box or package holds the two overlapping portions of the strap under comparatively high pressure during the tensioning process; consequently, there is considerable frictional resistance to the sliding of the sections upon each other. By providing the lubricating clip described above the free end of the strap can be lubricated by merely pulling a portion of it beneath the roller 20 so that when this end of the strap is overlapped upon an intermediate portion during the tensioning process, the friction resistance will be very considerably reduced.

Mounted on the stand is a platform 5 adapted to support one end of a box or package, the other end of which may be supported on any convenient bench. The stand is further provided with a box 26 and a shelf 27 for reinforcing girths, tools or the like.

This stand can very quickly be run up to the proper distance from a fixed support, 25 as a bench or the like, then boxes can be quickly placed with one end resting on the support 5 and the other on the bench, the strap applied, in a very few seconds in the manner illustrated in Fig. 3, the box then 30 turned around end for end, another binder applied, the box removed and a new box placed in its place and so on in rapid succession. The use of the foregoing method, and apparatus in the practice of the foregoing method, has been found very efficient 35 to shorten the time necessary for the application of tensional binders to boxes and packages.

Having thus described my invention, I 40 claim:—

1. A method of strapping boxes and the like, which consists in arranging a coil of strapping, and a box to be strapped adjacent each other, the strapping axis of the box 45 parallel to the axis of the coil, and in then transferring a loop of strap from the coil to the box, by relatively threading the box through the loop, thereafter tightening said loop as a binder on the box and joining its 50 ends.

2. A method of applying tensional binder material to boxes or the like, which consists in suspending a coil of the binder material adjacent the end of a box, and in 55 transferring a loop sidewise from the coil, along the axis of the coil to a position where it extends around the box, and in tightening and joining said loop about the box.

3. Apparatus useful for applying tensional binding material to boxes and the like, comprising a stand having thereon a support adapted to receive a coil of binding material and maintain the same in approx-

imately vertical position, and a support adapted to maintain one end of a box or 65 package adjacent to said coil.

4. A stand useful for applying tensional box strap or the like to boxes and packages, having an arm thereon adapted to project through a coil of strap or the like and a releasable clip wherein one end of said strap or the like may be releasably engaged.

5. In apparatus of the class described, a coil support, and an adjacent box support 70 so relatively arranged than an inner convolution of the coil may readily be transferred from the coil to a box on the box support.

6. In apparatus of the class described, and in combination, a coil support adapted to 80 support a coil in approximately upright position, an arm extending through the coil, and a clip on the arm.

7. In apparatus of the class described, and in combination, a coil support adapted to 85 support a coil in approximately upright position, an arm extending through the coil, and inclined upwardly, and a clip on said arm.

8. In apparatus of the class described, and in combination, a coil support adapted to 90 support a coil in approximately upright position, an arm extending through the coil freely, a clip on said arm, and a support for a box arranged adjacent the coil support and adapted to support one end of a box in position adjacent the coil so that 95 loops of the coil may be transferred sideways to the box.

9. In apparatus of the class described, and 100 in combination, a coil support adapted to support a coil in approximately upright position, an arm having a clip projecting through the coil, and a support for a box and projecting through the coil on said coil 105 support.

10. In apparatus of the class described and in combination, a coil support including an arm adapted to project through the coil, a clip for a strap end, and a box support adjacent said arm, all so relatively arranged that convolutions of the coil may 110 readily be transferred to the box by moving them along the coil axis.

11. The combination with a frame for 115 supporting a coil in approximately upright position of an arm having a clip for securing the free end of the coil, the said clip comprising means for holding said free end and for lubricating it as it is withdrawn from 120 said clip.

In witness whereof, I hereunto subscribe my name this 6th day of June, A. D. 1921.

JOHN W. LESLIE.

Witness:

OLIVER H. PARMELEE.
